Atty.

UNITED STATES PATENT OFFICE

ALFRED LANSER, OF CORSEAU-VVEVEY, SWITZERLAND

BURNER

Application filed August 10, 1929. Serial No. 385,030.

My invention relates to burners for heavy oils and analogous combustibles.

As is known in the art, it has already been proposed to dispose the needle valve of the 5 atomizer or other element from which leaves the combustible spray in the bottom of a sort of deflector composed of a cup in the form of a spherical cap or cone in order to cause the flame to be drawn back toward the 10 atomizer. The result expected has been exceeded. As a matter of fact the flame approaches the atomizer up to the point where it begins at the needle valve orifice even, which has the disadvantage of producing at 15 the said orifice a certain amount of carbon which rapidly closes the said orifice.

My invention has chiefly for an object not only to overcome the above indicated disadvantage but also to diminish the risks of accidental extinction of the said burners and to assure a better combustion of the fluids feeding the said burners.

My invention will be more readily understood by those skilled in the art to which my 25 invention pertains in the following description when taken in connection with the accompanying drawings forming a part of this specification and in which—

Fig. 1 is a section taken through my deflector along the line 1—1 of Fig. 2;

Fig. 2 is a front elevational view thereof; and

Fig. 3 is a section through a burner with my improved deflector applied thereto.

In the following description my invention 35 will be described as applied to an atomizer or other apparatus for spraying the combustible.

By any suitable process and any suitable 40 material I construct an element a , preferably cast of steel, which element comprises a substantially frusto conical portion a^1 forming the deflector so to speak and a cylindrical part a^2 for the purpose of mounting the said deflector which is to receive it.

The said cone is provided with a number 45 of small sleeves a^{11} whose axis is substantially tangential and directed toward the larger 50 base of the cone a^1 but at the same time form-

ing a certain angle with the generatrix which cuts the said axis.

I further provide on the cone a^1 between the part a^2 and the sleeves a^{11} a series of cylindrical holes a^{12} .

I likewise provide between the sleeves a^{11} and the base of the cone a^1 two series of tapered cylindrical holes a^{13} .

As shown in Fig. 3 the said conical member is attached to an atomizer b by any suitable means.

As concerns the disposition of the deflector a in the furnace mouth or combustion tube c I have determined by experiment that the said distance follows a constant law which establishes that the distance d of the base of the cone from the furnace mouth must equal the diameter D of the said furnace mouth. The outlet of member C may be slightly restricted as shown. This specific location of 70 the deflector has been found to improve the character of the flame under varying conditions of the velocities of the fuel and the air.

The flame of a burner produced according to the invention is better regulated than in 75 burners of the prior art. The said flame originates at a very short distance from the orifice which emits the spray and no carbon is produced at the orifice. In addition the position of the deflector with respect to the 80 furnace mouth and the said deflector being perforate itself establishes not only a better mixture of the comburant and the combustible but also utilizes the entire reverberation 85 of the flame.

As shown in Fig. 3, I preferably dispose a small tube e perpendicularly in the wall of the deflector of the atomizer which has its ends parallel with the axis of the atomizer. Beneath the tube e I provide the furnace 90 mouth wall with a small depression or drain opening c^1 for collecting drops of combustible which leak from the burner during stopping. I thus assure that there is no deposit of combustible in the furnace mouth which deposit 95 could readily become transformed into carbon when the apparatus is again started.

Having thus described my invention what I claim as new and desire to secure by Letters Patent is:

1. An oil burner comprising a combustion tube, a fuel atomizing nozzle in said tube, a substantially frusto-conical deflector surrounding said nozzle having a plurality of 5 openings in the side wall thereof, and apertured sleeves aligned with some of said openings and projecting from the outer wall of said deflector along lines extending toward the larger base of and substantially tangential to the outer periphery of said frusto-conical deflector.

2. An oil burner comprising a combustion tube, a fuel atomizing nozzle in said tube, a substantially frusto-conical deflector surrounding said nozzle having a plurality of 15 openings in the side wall thereof, and apertured sleeves aligned with some of said openings and projecting from the outer wall of said deflector along lines extending toward the larger base of and substantially tangential to the outer periphery of said conical deflector, the larger base of said frusto-conical deflector being spaced from the outlet of said combustion tube a distance substantially 20 equal to the internal diameter of said tube.

3. An oil burner comprising a combustion tube, a fuel atomizing nozzle in said tube, a substantially frusto-conical deflector surrounding said nozzle having a plurality of 30 openings in the side wall thereof, and apertured sleeves aligned with some of said openings and projecting from the outer wall of said deflector along lines extending toward the larger base of and substantially tangential to the outer periphery of said frusto-conical deflector, some of said openings disposed 35 on both sides of said apertured sleeves.

4. An oil burner comprising a combustion tube, an atomizer nozzle in said tube, a substantially frusto-conical deflector surrounding said nozzle, an oil drain opening in the bottom of said combustion tube, and a short tube extending through the side wall of said conical deflector having one end disposed beneath said atomizer nozzle and its other end over said drain opening, the ends of said short tube being spaced from nozzle and drain opening.

50 In testimony whereof I have affixed my signature.

ALFRED LANSER.
